UNITED STATES PATENT OFFICE.

WILLIAM J. JUDD, OF NEW YORK, N. Y., ASSIGNOR TO FREDERICK C. AUSTIN, OF CHICAGO, ILLINOIS.

MIXING-MACHINE FOR CONCRETE OR THE LIKE.

SPECIFICATION forming part of Letters Patent No. 781,727, dated February 7, 1905.

Application filed March 16, 1903. Serial No. 148,019.

To all whom it may concern:

Be it known that I, WILLIAM J. JUDD, a citizen of the United States, residing at New York, in the county of New York and State of New York, have invented certain new and useful Improvements in Mixing-Machines for Concrete or the Like, of which the following is a specification.

My invention relates to machines for mixing concrete and the like in which the materials are introduced into a mixing-receptacle supported to revolve about a tilting axis, the mixing-receptacle thus charged with materials being revolved about said axis to effect the mixing and being tilted at a proper moment for the purpose of discharging the mixed-up batch.

Objects of my invention are to rapidly and effectively mix the materials introduced with in the mixing-receptacle; to secure a quick and clean discharge from the mixing-receptacle; to cause the mixed-up batch to be automatically discharged by the rotary action of the mixing-receptacle; to avoid all necessity for providing the rotary mixing-receptacle with mixing-blades or the like, thereby dispensing with objectionable internal projections to which concrete and the like is apt to adhere to an extent to preclude a clean and complete discharge; to reduce the time consumed in the operation of charging, mixing, and discharging; to charge the mixing-receptacle without causing the materials to clog the passage provided for their introduction; to provide an improved chute or hopper device adapted for directing materials into a rotary tilting mixing-receptacle during the rotation of the latter and operated to automatically swing away from a charging position when such receptacle is tilted to discharge the mixed-up batch; to insure certainty of action and proper relative positions on the part of the automatic chute or hopper; to provide a compact, convenient, and efficient portable mixer which can be readily drawn from place to place along roads or streets and positioned for mixing up concrete for sidewalks and the like; to readily and conveniently supply the mixer with water in suitable quantity during opera-

tion; to effect the discharge of a mixed-up batch at a convenient point; to provide a simple and efficient construction and organization of power-transmitting mechanism arranged between an engine or motor and the rotary mixing-receptacle and adapted to continuously revolve the mixing-receptacle, whereby the latter can be tilted without arresting its rotative action; to provide a construction and arrangement whereby the rotary tilting mixing-receptacle, the engine or motor, and the intervening power-transmitting mechanism are compactly and conveniently mounted upon a comparatively light wheeled carriage, and to provide certain novel and improved details of construction and arrangement in mixing-machines for concrete and the like.

In the accompanying drawings, Figure 1 is a side elevation of a mixing-machine embodying my improvements. Fig. 2 is a top plan view of the same. Fig. 3 shows the machine in end elevation. Fig. 4 is a longitudinal vertical section on line *xx* in Fig. 2, the mixing-receptacle being shown in position for receiving and mixing. Fig. 5 is a like section with the mixing-receptacle in position for discharging its contents, the engine being omitted.

A indicates a carriage having front and rear wheels B and C and having its body-frame 1 supported upon and above the front and rear axles for such wheels, so as to suitably elevate the rotary mixing-receptacle D, which is in turn supported to tilt upon the body-frame. The carriage thus constructed can be drawn along a road or street by one or more horses, and to such end it is desirably provided with a suitable tongue where two horses are employed or with shafts 2 when one horse is deemed sufficient. The rotary mixing-receptacle is arranged to discharge at the rear end of the carriage and is arranged back of an engine or motor E, which is mounted upon the body-frame of the carriage and employed for rotating the mixing-receptacle, the driving connection between the motor or engine and the mixing-receptacle being preferably arranged to permit the continuous rotation of the mixing-receptacle during the successive

operations of charging, mixing, and discharging. The motor or engine may be of any approved type or construction, the motor represented being an ordinary gasoline-engine. 5 The mixing-receptacle is indirectly supported upon the body-frame of the carriage by means of a tilting frame F, which is pivoted between its ends upon the body-frame by means of suitable trunnions or side journals. In the construction illustrated the longitudinal side bars 3 of the tilting frame are arranged opposite the outer sides of the longitudinal side bars 4, Fig. 2, of the body-frame and are rigidly connected together at points in rear of the mixing-receptacle by cross-bars 5 and 6, which serve to support a portion of the driving mechanism, the cross-bar 5 also affording a support for the rear journal 7, Fig. 4, of the mixing-receptacle. With this arrangement the cross-bars 5 and 6 extend over the side bars of the body-frame and rest thereon when the mixing-receptacle is in mixing position, as in Fig. 4, whereby the mixing position of such receptacle is readily determined. The portion of the mixing-receptacle at which the discharge takes place is indirectly supported upon a cross-bar 8, Fig. 3, at the rear end of the tilting frame. When the axis about which the mixing-receptacle is horizontal, as in Fig. 4, the rear cross-bar of the tilting frame will lie in a horizontal plane parallel with but below the plane of the rear cross-bars 5 and 6, this relative drop on the part of the rear cross-bar being, for example, attained by mounting the end portions of the rear cross-bars 5 and 6 upon the side bars 3 of the tilting frame and securing the front cross-bar 8 to the under sides of the said side bars 3, and in this way when the mixing-receptacle is in mixing position the rear cross-bar 8 of the tilting frame will bear against the under sides of the side bars 4 of the carriage frame or body.

The mixing-receptacle illustrated is a cubiform box supported to revolve about a tilting axis passing through diagonally opposite corners and having one of such vertices or corners cut away to provide an opening through which the material is ejected when such axis is properly inclined. In order to form this corner portion of the box or receptacle with a suitable opening, it is desirably constructed with a plate 9, Fig. 5, having a circular opening and an annular flange about such opening and forming a short neck 10, through which the mixed-up batch passes when the box is in position for discharge, as in Fig. 5. The plate 9 is also provided with an outer annular flange 11, concentric with the flange 10, Fig. 3, and forming a journal 60 which bears upon antifriction-rolls 12 on the rear cross-bar 8 of the tilting frame. The discharge opening or passage 13 is coincident with the tilting axis about which the mixing box or receptacle revolves and is arranged for

discharging a mixed-up batch at the rear end 65 of the carriage, which has a greater spread to its rear wheels than to its front wheels, so that when the mixing-receptacle is in position for discharge, as in Fig. 5, an ordinary wheelbarrow can be placed under the discharge-opening to catch the batch discharged. 7c

While the mixing-receptacle can be provided with a side door which can be opened for the purpose of charging the mixing-receptacle when the rotation of the latter is arrested, I prefer to employ the opening 13 for both charging and discharging, it being observed that said opening is coincident with the tilting axis about which the mixing-receptacle revolves. The mixing-receptacle 80 (shown in the form of a cube box) has the opening 13 at one corner portion and is provided at its diagonally opposite corner portion with a hollow journal 7, coincident with the axis of rotation and supported by a bearing 14, which is arranged upon cross-bar 5 of the tilting frame and provided with suitable means for oiling, such as an oil-cup 15. The hollow journal 7 permits the introduction of water into the mixing-receptacle, and to such end a pipe G is extended through the hollow journal 7 and at its outer end connected with a flexible hose-pipe 16, which can be extended to and connected with any suitable source of supply—such, for example, as an ordinary 95 street connection for such hose-pipe. The pipe G is secured to the tilting frame F—as, for example, to the rear cross-bar 6 of said frame—it being seen that when the tilting frame which thus carries the pipe G is tilted the flexible 100 hose will permit such movement on the part of the tilting frame. Upon the outer end portion of the journal 7 is secured a bevel-gear H. This bevel-gear H is engaged by a pinion 17, Fig. 2, which is fixed upon a short 105 transversely-arranged counter-shaft 18. This counter-shaft 18 is supported by bearings 19 and 20 on the tilting frame and has at one end a belt or sprocket wheel 20, Fig. 1, which said sprocket-wheel is connected by an endless link 110 belt 21 with a smaller sprocket 22, arranged to revolve about an axis transverse to the axis of rotation of the mixing-receptacle and constituting the horizontal axis about which the mixing-receptacle tilts. The sprocket 22 is therefore arranged to revolve about one of the journals or trunnions 23 for the tilting frame, and in order to gear-connect it with the rotary engine-shaft 24 it is formed upon or secured to a belt-wheel 25, which is in turn 115 connected with a belt-wheel 26 on the engine-shaft by means of an endless belt 27. With this arrangement the belt 27 is parallel with and arranged alongside of one of the side bars 3 of the tilting frame and the link belt 21 is arranged between and parallel with one of said side bars 3 of the tilting frame and the power-transmitting belt 27, thereby providing 120 125

ing a simple and compact driving arrangement and also permitting the frame F, which carries the counter-shaft 18, to readily tilt.

In order to readily charge the mixing-receptacle, a swinging chute or hopper I is supported upon the tilting frame and arranged to automatically swing into position for directing materials into the mixing-receptacle when the latter is in mixing position, as in Figs. 1 and 4, and to automatically swing away from the discharge-opening when the mixing-receptacle is in position for discharge, as in Fig. 5. As a means for thus automatically actuating the hopper I it is pivotally supported upon the tilting frame and connected with the body-frame of the carriage by an operating device which causes the hopper to swing as the result of relative movement between the tilting frame and the body-frame of the carriage. As best shown in Fig. 3, the hopper is secured to and suspended from a rock-shaft 28, which is in turn supported by an upright frame 29 on the rear cross-bar 8 of the tilting frame. This rock-shaft 28 is provided at one end with a crank-arm 30, which has a pivotal connection with a fixture, such as a bar 31, secured upon the body-frame of the carriage. When therefore the mixing-receptacle is tilted from the position shown in Fig. 4 to the position shown in Fig. 5, the relative movement between the tilting support and the body-frame of the carriage will cause the hopper to swing away from the discharge-opening, as in Fig. 5, and when the tilting frame is swung back into the position shown in Fig. 4 the hopper will be brought into position to discharge the materials well into the opening 13 of the mixing-receptacle. The tilting frame is also provided with a short trough or deflector K, which is secured upon the rear end of the tilting frame and arranged to properly direct the discharged batch when the mixing-receptacle is in position for discharge, as in Fig. 5, it being observed that this short trough K is shown concave in cross-section and has its inner end adapted to the external contour of flange 10 on plate 9 of the mixing-receptacle.

In the construction of mixing-machine shown the polyhedral or cubiform mixing box or receptacle is both charged and discharged through an opening at one of its corner portions, and it can be thus charged and discharged while revolving about an axis extending through the single opening thus provided. When the axis of rotation of such box is horizontal, or substantially so, the chute or hopper will be in position to project into the opening 13, and thereby direct the materials into the box, and by this arrangement the passage formed by such opening 13 may be of sufficient length to also adapt it for a discharge-passage, while by thus projecting the lower end of the hopper within such passage the materials will be directed into the box to

an extent to prevent accumulation of materials in the passage referred to. When the box is revolved in mixing position, the materials will be rapidly and effectively mixed without the use of blades or stirrers, and when the box is tilted into position for dumping the mixed-up batch the latter will be ejected by the rotary action of the box, which in thus revolving constantly changes the angles of its inner sides relatively to a horizontal line and causes all of the corners of the box excepting the two diagonally opposite corners, through which the axis of rotation passes, to swing round in planes which incline upwardly and forwardly, thereby carrying the material toward the discharge side of the machine. The corner portion of the box which is diagonally opposite the corner portion through which the inlet and outlet opening is formed is practically a closed corner through which a small pipe 85 may be inserted by way of an axial perforation made for such purpose, and when desired the water-supply pipe can be omitted and the journal 7 can be made solid. By thus practically closing the box at the front and charging and discharging at the rear portion thereof the motor or engine can be set comparatively close to the box and the journal 7 can be mounted direct in bearing 14 and be extended beyond the same, so as to carry the gear H, thereby dispensing with supporting-rolls and providing a simple and mechanically-desirable support at this point, it being observed that in the machine illustrated it would be both inconvenient and undesirable to attempt to so open the practically closed corner referred to as to permit the box to be charged at this point. By charging and discharging at the rear corner room is afforded for the deflector K, which prevents material from sifting onto the rolls 12 and getting in between the journals of such rolls and their bearings, and the driving mechanism can be placed whereby it will be out of the way of materials delivered to the box.

What I claim as my invention is—

1. In a machine for mixing concrete and other materials, a rotary mixing-receptacle provided with an opening for the passage of material in line with its axis of rotation; a tilting support for the rotary mixing-receptacle; a movable chute or hopper arranged upon the tilting support and movable in directions to alternately place it in and out of position to deliver materials into said opening in the hopper; and a device for operating the chute or hopper automatically actuated from the tilting action of the tilting support for the mixing-receptacle.

2. In a machine for mixing concrete and the like, a mixing-receptacle supported to revolve about a tilting axis and having an opening for the passage of material coincident with such axis; a tilting frame whereon the rotary mixing-receptacle is mounted; a support for the tilting frame; a chute or hopper supported to

- swing upon the tilting frame and arranged to swing into place to discharge into the opening of the rotary mixing-receptacle when the latter is brought into position for mixing, and to swing away from such opening when the rotary mixing-receptacle is brought into position for discharge; and a power-transmitting connection arranged between the swinging hopper and the support for the tilting frame and actuated by relative movement between the tilting frame and its support to effect said movements on the part of the swinging chute or hopper.
3. In a machine for mixing concrete and the like, a mixing-receptacle supported to revolve about a tilting axis and having coincident with such axis an opening for charging the mixing-receptacle with materials and for discharging the mixed-up batch; a tilting frame whereon the rotary mixing-receptacle is mounted; a support for the tilting frame; a chute or hopper supported to swing upon the tilting frame and arranged to swing into place for discharging into said opening of the rotary mixing-receptacle when the latter is brought into position for mixing, and to swing away from such opening when the rotary mixing-receptacle is brought into position for discharging its contents; and a power-transmitting connection arranged between the swinging hopper and the support for the tilting frame and actuated by relative movement between the tilting frame and its support to effect said movements on the part of the swinging chute or hopper.
4. In a machine for mixing concrete and the like, a rotary mixing-receptacle arranged to swing about a tilting axis and having coincident with such axis an opening for the passage of material; a tilting frame whereon the rotary mixing-receptacle is mounted; a support for the tilting frame; a chute or hopper hung to swing upon the tilting frame; and a power-transmitting connection between the chute or hopper and the support for the tilting frame comprising a crank applied for swinging the hopper, and connection between the crank and the support for the tilting frame, the hopper being arranged and actuated to swing into place to discharge into said opening of the mixing-receptacle when the latter is brought into position for mixing, and to swing away from such opening when the mixing-receptacle is brought into position for discharge.
5. In a machine for mixing concrete and the like, a mixing-receptacle supported to swing about a tilting axis and having coincident with such axis an opening for the passage of material; a tilting frame supporting the rotary mixing-receptacle; a support for the tilting frame; a hopper arranged to swing into place for discharging into said opening in the rotary mixing-receptacle and to also swing away from such opening; a crank-shaft mounted upon the tilting frame and forming a rod-shaft to which the hopper is attached; and connection between the crank of said shaft and the support for the tilting frame as a means for swinging the hopper into place for charging the mixing-receptacle when the latter is brought into position for mixing, and for swinging the hopper away from the mixing-receptacle when such receptacle is moved into position for discharging its contents.
6. In a machine for mixing concrete and the like, a carriage comprising a body-frame supported by front and rear wheels; a tilting frame pivotally supported upon the body-frame and arranged to tilt about an axis transverse to the length of the body-frame; a cubiform mixing-receptacle supported at diagonally opposite corner portions upon the tilting frame and arranged to revolve about an axis passing through said corner portions, said cubiform mixing-receptacle being provided at the rear one of such corners with an opening for the passage of material coincident with the tilting axis about which it revolves; a movable chute or hopper supported upon the rear end portion of the tilting frame and arranged to move into place to charge the mixing-receptacle through said rear opening when the mixing-receptacle is tilted into position for mixing and to move away from the mixing-receptacle when the latter is tilted into position to depress said opening and permit the rotation of the mixing-receptacle to effect the discharge of a mixed-up batch through the opening thus depressed; a device actuated by relative movement between the tilting frame and the body-frame and adapted to automatically effect said movements on the part of the chute or hopper; an engine or motor mounted upon the body-frame forward of the mixing-receptacle; and power-transmitting gear connection between the engine or motor and the mixing-receptacle for rotating the latter.
7. In a machine for mixing concrete and the like, a cubiform mixing-receptacle supported to revolve about a tilting axis passing through diagonally opposite corner portions and open at one of such corner portions for the passage of material while it is revolving, the opposite one of said corner portions being provided with a journal; a tilting support upon which the rotary cubiform mixing-receptacle is mounted, and having antifriction-rolls engaging a bearing at the rear one of said corner portions, and a bearing for the journal at the diagonally opposite corner portion; a gear-wheel fixed upon said journal; an engine or motor; power-transmitting gearing supported upon the tilting frame and connecting the gear on the journal at one corner portion of the mixing-receptacle with a gear-wheel mounted to revolve about the axis about which the tilting frame is arranged to tilt; and driving connection between the engine or motor and

the gear-wheel thus mounted to revolve about said axis about which the frame tilts.

8. In a machine for mixing concrete and the like, a carriage comprising a body-frame supported by front and rear wheels; a tilting frame constructed with side bars pivotally supported upon the body-frame and arranged parallel with and beyond the longitudinal sides of such body-frame, and having a transverse front end portion arranged over the body-frame; a rotary mixing-receptacle supported to revolve upon the tilting frame and open to discharge at the rear of the carriage; an engine or motor mounted upon the carriage forward of the mixing-receptacle; and driving connection between the engine and the mixing-receptacle for revolving the latter.

9. In a machine for mixing concrete and the like, a cubiform mixing-box arranged to revolve about a tilting axis passing through diagonally opposite corners, one of such corners being practically closed, and the other being open to provide a passage for charging and discharge while the box is revolving, and the box being supported at its open corner portion by antifriction-rolls, and being provided at said practically-closed corner with a journal; a tilting frame carrying said rolls and having a bearing for said journal; an engine or motor; and power-transmitting connection between the engine or motor and the said journal.

10. In a machine for mixing concrete and the like, a carriage comprising a wheeled body-frame; a tilting frame pivotally supported between its ends on the wheeled body-frame; a rotary mixing-receptacle supported upon the tilting frame; an engine or motor mounted upon the wheeled body-frame; a transversely-arranged counter-shaft supported upon the tilting frame and gear connected with the rotary mixing-receptacle; a sprocket-wheel supported upon the wheeled body-frame and having its axis coincident with the axis about which the tilting frame tilts; a link-belt connecting said sprocket with a sprocket on said counter-shaft; and power-transmitting-belt connection between the engine or motor and a belt-wheel rigid with the sprocket having as its axis the axis about which the tilting frame tilts.

11. In a machine for mixing concrete, a carriage comprising a wheeled body-frame; a tilting frame pivotally supported between its front and rear ends upon the wheeled body-frame; a rotary mixing-receptacle mounted upon the tilting frame; a swinging hopper supported upon the rear end portion of the tilting frame; an engine or motor mounted upon the wheeled body-frame; driving-gear arranged upon the tilting frame forward of the mixing-receptacle and connecting with the latter; and driving-gear supported upon the wheeled body-frame and connecting the

driving-gear on the tilting frame with the engine or motor.

12. A machine for mixing concrete and the like, comprising the wheeled carriage A; the tilting frame F supported upon the wheeled carriage; the rotary mixing-receptacle mounted upon the tilting frame; an engine or motor mounted upon the wheeled carriage at a point forward of the tilting frame; a swinging chute or hopper supported upon the rear end portion of the tilting frame; power-transmitting connection between the engine or motor and a chain or sprocket wheel having as its axis of rotation the transverse axis about which the tilting frame operates; and power-transmitting connection between said chain or sprocket wheel and the mixing-receptacle and involving a chain or belt 21 connecting such chain or sprocket wheel with a chain or sprocket wheel which is mounted upon the forward end portion of the tilting frame and arranged to revolve about an axis parallel with the axis about which the tilting frame operates.

13. In a machine for mixing concrete and other materials, a carriage provided at its forward end with an engine or motor; a longitudinally-arranged frame supported to tilt about an axis between its front and rear end portions and transverse to the carriage-body, said tilting frame being arranged with its forward end in rear of the engine or motor and its rear end at the rear end portion of the carriage; a mixing-receptacle supported to revolve upon the tilting frame about an axis parallel with the length of the carriage and having its rear end open at the rear end of the carriage to receive and discharge material, and its forward end practically closed by a journal supported upon the tilting frame; and driving mechanism for the rotary mixing-receptacle connecting the latter with the engine or motor and in part supported on the tilting frame and in part supported on the body of the carriage.

14. In a machine for mixing concrete, a rotary mixing-receptacle having journals, and an opening for inlet and outlet of material, coincident with its axis of rotation; a tilting support upon which the rotary mixing-receptacle is supported for rotation independent thereof; a gear fixed upon one journal of the rotary mixing-receptacle; a pipe extending axially through the said journal which is formed with an axial passage suitable to admit such pipe, the pipe thus arranged being secured upon the tilting frame; and a flexible supply-pipe connected with the pipe which thus extends through the journal of the rotary mixing-receptacle.

WILLIAM J. JUDD.
